UNITED STATES PATENT OFFICE.

MARCUS STEVENS, OF DETROIT, MICHIGAN.

PICTURE-FRAME.

SPECIFICATION forming part of Letters Patent No. 223,613, dated January 13, 1880.

Application filed May 24, 1879.

To all whom it may concern:

Be it known that I, MARCUS STEVENS, of Detroit, in the county of Wayne and State of Michigan, have invented an Improvement in Picture-Frames, of which the following is a specification.

The nature of my invention relates to improvements in the construction of picture-frames, whereby one of the members of said frame is made by the art of upholstery in any desired color, to give tone to the picture, or to correspond to the general colors of the furniture of the apartment.

The invention consists in the construction of a picture-frame of any desired shape or size, as more fully hereinafter set forth.

Figure 1 is a front elevation. Fig. 2 is a section on the line $x x$ in Fig. 1, and Fig. 3 is a section on the line $y y$.

In the accompanying drawings, which form a part of this specification, is shown a rectangular frame, consisting of the outer member, A, and the inner member, B, which are constructed in the usual manner, and may be gilt, or finished in any desired style or coloring,

which should form a contrast to the center member, C, which is made by the usual process of upholstering, and covered with satin or other textile fabric, which may be Shirred, plaited, puffed, or plain, as taste may dictate, 30 and the color of such covering should form a pleasing contrast to the other members of the frame, and at the same time be such as to give tone to the coloring of the picture and correspond generally to the coloring of the furniture 35 in the apartment.

These frames may be rectangular, round, oval, or any other desired form.

What I claim as my invention is—

As a new article of manufacture, a wooden 40 picture-frame with an angular face, and having the angle filled with the raised padded portion C between the outer and inner wood moldings, A B, substantially as described and shown.

MARCUS STEVENS.
